JAMES W. STOCKING, OF HOLLYWOOD, CALIFORNIA.

ELECTRIC SWITCHING.

Application filed September 23, 1926. Serial No. 137,253.

This invention relates to electric switching and particularly to an electric circuit controller for use in theatre lighting.

In order to secure the desired lighting effects in theatrical productions, and particularly the smooth transition from one lighting effect to another, it is necessary to take care of a number of unusual switching problems. The various theatre lights are arranged in 10 different banks, and most of these banks require not only individual control, but also control from a master, so that several banks may be switched at the same time. In certain cases, it is also desirable to control the 15 various master switches by a main master so that the various sets of banks will be switched on or off at the proper time.

Considering a single bank of lights, experience has shown that the following controls or control positions are desirable in 20 order to secure all the effects required:

- (a) An off position.
- (b) An on position.

(c) A complete transfer position in which 25 the switch for the particular bank of lights is out of operation and the entire bank is controlled from a master switch. In this position the lights should be capable of being turned on or off from the master switch regardless of whether they were on or off when 30 the bank switch is moved to the complete transfer position.

(d) A "transfer off" position. In this 35 position of the bank switch, if the lights are on when the transfer is made and the master switch is also on, the lights continue to burn, but if the master switch is then shifted to off position it will not thereafter turn the lights on.

(e) A "transfer on" position. In this 40 position, if the lights are off when the transfer is made, the lights will stay off even though the master switch is at on position, but if the master switch is then turned off and then on, the lights will come on.

The systems in use today for securing these 45 results comprise a large number of independent switches arranged in special switchboards. The systems are highly expensive, not only to purchase, but also to operate. The switchboards are necessarily so large 50 that several men are generally required to operate them, and this is undesirable not only because of the additional expense, but

also because valuable space is taken up and 55 the wiring connections are unduly complicated.

I provide a single switch which may be placed within a very small compass, and which is effective for giving all of the above 60 recited controls. On this account it is possible to provide a very large number of such switches at a single control station and thus reduce the space taken up, and cut down the operating expense due to the elimination 65 of one or more electricians.

The accompanying figure of drawings illustrates diagrammatically the present preferred embodiment of my invention. Two bank switches are shown, each of them being 70 connected to a master switch, the master switches in turn being connected to a main master switch.

In the illustrated embodiment of the invention, there are illustrated lamp banks 2 and 75 3 which are required to be controlled. Current is supplied from mains L—1 and L—2 and one branch of the circuit to the lamp banks is made through wires 4 leading from the main L—1. If desired, a dimmer 5 may 80 be inserted.

The lighting circuit for either of the banks 2 and 3 is completed through a wire 6 terminating in one of a pair of contacts 7. The other contact is connected back to the main 85 L—2 through a wire 8.

The circuit is normally open, as shown in the drawings, and a bridge 9 is provided for closing the circuit. The bridge 9 is connected to the plunger 10 of a solenoid 11, 90 and this solenoid is in turn controlled by my improved switching means.

In the drawings each bank switch is shown 95 diagrammatically as a drum type controller having a bridge member 12, with contact portions 13 and 14 therein. This bridge member 12 is adapted to occupy the positions indicated by heavy horizontal chain lines in the drawing. These chain lines are marked with the five positions above enumerated and the operation for each of these positions will be described in turn.

(a) Off position.

When the bridge member 12 is in the off 100 position, no contacts of any sort are made, and since the bridge member 9 is in low position

as shown in the drawings, the lights do not burn.

(b) *On position.*

5 When the bridge member 12 is in the on position, current flows from the main L-1 through a wire 15 to a terminal 16, thence through the contact portion 14 to a terminal 17. From the terminal 17 it flows through 10 a wire 18 to a terminal 19, through a switch member 20 and a wire 21, to the solenoid 11 and thence back to the main L-2 through a wire 22. The switch member 20 is pivoted at 23 and is normally held in the position 15 shown by a spring 24.

The circuit above recited constitutes the closing circuit for the solenoid or closing coil 11. It is effective for pulling the bridge member 9 upwardly towards the terminal 7.

20 The bridge member 9 is provided with an insulated extension 25 having a terminal 26 therein, adapted to engage an extension or finger 27 on the switch 20. The terminal 26 is connected through a wire 28 to a terminal

25 29, which is in contact with the contact portion 14 in the on position. Therefore, as soon as the terminal 26 engages the finger 27 current is free to flow through the wire 15, the contact portion 14, the wire 28 and the 30 wire 21 to the solenoid 11, and thence through the wire 22 to the main L-2. This constitutes the holding circuit for the closing coil or solenoid 11.

Obviously, as the plunger 10 moves upwardly it will tend to break the connection between the terminal 19 and the switch member 20, but the operation of the closing coil 11 will remain unaffected, since the circuit will be maintained through the holding circuit above described.

40 When the bridge member 9 is in its upper position, the circuit for the lamp bank is completed and the lights will burn and continue to burn so long as the bridge member 12 remains in the on position. If it is shifted back to the off position both the holding and the closing circuits will be broken, the bridge member 9 will drop and the lamps will go out.

(c) *Complete transfer position.*

45 As above stated, it is necessary in this position to put the lamp bank under the control of the master switch so that the lights may be turned on or off from such master switch. Assuming that the master switch is on, and the contact member 12 is moved from the on position to complete transfer position, the lights should remain burning and moreover should not flicker during the time of the 55 transfer. If the master switch is off and the contact member 12 is moved from the on position to the complete transfer position, the lights, of course, should go out.

60 The master switch comprises a bridge member 30 having contact portions 31, 32 and 33

and adapted to occupy an off position, an on position and a transfer position, as shown in the drawing. When the bridge member 30 is in the on position, the contact portion 33 bridges a pair of contact members 34 and 35. 70 With the bridge member 12 at the complete transfer position, and the bridge member 30 at the on position, an electrical path is established from the main L-1 to the main L-2 as follows:—Through the wire 15 to terminal 16, through a wire 36 and a wire 37 to contact member 34 through contact portion 33, to contact member 35, through a wire 38 to a contact member 39, thence through contact portion 14 and contact member 29, through wire 80 28, terminal 26, switch finger 27, wire 21, solenoid 11 and wire 22. It will be recalled that the bridge member 12 has been moved from on position to complete transfer position, and therefore, the bridge member 9 will be up. It 85 will be noted that the contact members 16 and 39 overlap so that no flickering of the lights occurs during the movement of the bridge member 12.

Now assume that the bridge member 30 is 90 shifted to the off position, while the bridge member 12 remains at complete transfer position. The circuit is immediately broken, the solenoid is deenergized, the bridge member 9 drops and the lamps go out.

95 Now assume that the bridge member 30 is again moved to the on position. Current flows through the wires 15, 36 and 37 to the contact member 34, thence through the contact portion 33 to the contact member 35, to 100 the wire 38. Current cannot flow through the wire 28 because the circuit is open between the terminal 26 and the switch finger 27. However, a closing circuit is provided by a branch wire 40 terminating in a contact member 41. The contact member 41 is engaged by the contact portion 13 of the bridge member 12 and current is free to flow through this contact portion 13 to a contact member 42, thence through a wire 43 connected into 105 the wire 18. With the closing circuit thus established, the operation of the solenoid and its connected switch mechanism is the same as was described for the on position.

(d) *Transfer off position.*

110 With the bridge member 12 in the transfer off position, the contact member 39 and the contact member 29 are joined by the contact piece 14. Since both the contact members 39 and 29 extend from the complete transfer position, and also since the master switch is at the on position when the bridge member 12 is moved to transfer off position, the holding circuit through wires 15, 36 and 37, contact member 34, contact portion 33, contact member 35, wire 38, contact member 39, contact portion 14, contact member 29, wire 28, terminal 26, switch 27, wire 21, holding coil 11 and wire 22 is maintained. If, however,

the master switch is moved to off position, the circuit is broken and since the closing circuit for the holding coil 11 cannot be completed with the bridge member 12 in transfer off position, the lights will remain off, thus fulfilling the requirements of the transfer off position.

(e) Transfer on position.

As stated heretofore, the five position control is preferably of the drum type, and it is therefore possible to go from the off position direct to the transfer on position. Assume, therefore, that the bridge member 12 is moved from the off position to the transfer on position, and that when this occurs the master switch is in the on position. It will be noted that while there is an electrical path through the wires 15, 36 and 37 to the contact member 34, thence through the contact portion 33, the contact member 35, the wire 38, the contact member 39, the contact portion 14, the contact member 29 and the wire 28 to the contact member 26, the circuit for the closing coil 11 will not be complete because the plunger 10 is in its lower position. The lamp bank, therefore, will not burn even though the master switch is in the on position.

Now assume that the bridge member 12 is left at transfer on position while the master switch is moved to the off position. At this point it must be mentioned that the drum of the master switch is provided with a suitable ratchet stop so that the movement from on position to off position can only be accomplished by a movement in the direction of the arrow A on the drawing. Obviously, the lights will still remain off, as no current can flow through the wire 15 with the bridge member 12 in the transfer on position unless it also flows through the master switch.

Now assume that the bridge member 30 is moved from off to on position in the direction of the arrow A. The contact member 33 not only bridges the contacts 34 and 35, but it is temporarily connected also to a contact portion 44. The closing circuit for the closing coil is established as follows:—From main L—1 through wires 15, 36 and 37 to contact member 34, through contact portion 33 to contact member 44, thence through a wire 45 to a contact member 46, thence through contact portion 13 on the bridge member 12 to a contact portion 47, thence through a wire 48 through contact member 42, wire 43, wire 18, terminal 19, switch 20, wire 21, coil 11 and wire 22 to main L—2. With the closing circuit thus established, the core 10 raises, the holding circuit is established through contact member 35, wire 38, contact member 39, contact portion 14, contact member 29, wire 28, terminal 26, switch finger 27, wire 21, coil 11 and wire 22.

As above stated, the master switch can only be shifted from on to off position in the

direction of the arrow A. However, it is desirable to shift from transfer to off position and vice versa without going through the on position and I therefore arrange the ratchet mechanism to permit of such shifting while at the same time preventing movement from on to off position, except in the direction of the arrow.

Joining of several bank switches to a single master switch.

Obviously, it is desirable to control a number of banks of lights from a single master switch so that the desired results may be obtained. I, therefore, provide a five position switch for each bank of lights to be controlled. Each of these switches will have its own wire 15, and holding coil 11, and the parts will be connected as shown in the drawings. In order to secure the desired connection with the master switch, I provide a branch wire 36' connected to the wire 36, and leading to a contact member 16 in another bank switch; a branch wire 45' connected to the wire 45 leading to a contact member 46 in another bank switch; and a wire 38' connected to the wire 38, connected to the contact members 39 and 41 of the other bank switch. Obviously, any number of bank switches may be paralleled in this manner and operated from a single master switch.

Transfer from master switch to main master switch.

The master switch is provided with a transfer position comprising four contact members 48, 49, 50 and 51. The contact member 48 is connected through a wire 52 to the contact member 35. The contact portion 32 on the bridge member 30 is adapted to bridge the contact members 48 and 49 and thus complete an electrical path from the contact member 35 on the master switch to a corresponding contact member 53 on the main master switch through a wire 54. The contact member 50 is connected to the contact member 44 through a wire 55 and the contact portion 31 is adapted to connect the contact members 50 and 51 and thus complete an electrical path from the contact member 44 to a corresponding contact member 56 through a wire 57. The main master switch is also provided with a contact member 58 corresponding to the contact member 34 and connected to the wire 36 through a wire 59. A bridge member 60 is provided for the main master switch, and this is also movable only in one direction, as indicated by the arrow B.

It will be noted that the bridge member 30 overlaps the on and transfer positions of the master switch. This prevents flickering of the lights in case the main master switch is in the on position and the master switch is moved from on position to transfer position.

The main master switch may control a

number of master switches, which each in turn control a number of lamp banks. In the drawing, two master switches are connected to the main master switch, but it will be understood, of course, that others may be connected in the same way.

If desired, suitable relay circuits may be employed instead of the simple circuits shown in the drawings. Instead of drum controls, 10 pan type controls may be employed and the various contact members arranged therein as segments of circles. In either case the space required for the entire control system is very materially reduced, and generally the 15 services of one or more electricians may be dispensed with. This not only represents material economies in operation, but also assures better results, since one man working at a relatively small control station can obviously time the various effects more accurately than can several men working at separated stations.

My improved switching means is not limited to the application illustrated, but may be 25 employed for the control of other power consuming devices, such for example, as a plurality of motors as are used to control drops and flies used for various scenes in theatre work. It will be understood, of course, that 30 the motors may simply be connected in the lines corresponding to 6 and 4 in place of the lamp banks illustrated.

I have illustrated and described a preferred 35 form of the invention, but it will be understood that the invention is not limited to such form, since it may be otherwise embodied within the scope of the following claims.

I claim:—

1. An electric circuit controller, including 40 a normally open main switch in the circuit to be controlled, a closing coil therefor, a closing circuit for the closing coil, comprising a terminal adapted for connection with a current source and a normally closed switch, a holding circuit for the closing coil comprising a terminal adapted for connection with the current source and a normally open switch, means operable upon closing of the main switch for opening the switch in the 45 closing circuit and closing the switch in the holding circuit, a bridge member, the bridge member having an "off position" wherein the terminals are not connected to the current source, an "on position" wherein the terminals are connected to the current source, and a "complete transfer" position, and complete transfer mechanism comprising a master switch having a pair of terminals and a bridge therefor, one of the terminals being 50 connected to a current source and the other terminal being connected to a contact means so positioned as to connect with the closing circuit through the first mentioned member when it is in the complete transfer position, 55 and also connected with the holding circuit

through said first mentioned bridge member when it is in the complete transfer position.

2. An electric circuit controller, including a normally open main switch in the circuit to be controlled, a closing coil therefor, a closing circuit for the closing coil, comprising a terminal adapted for connection with the current source and a normally open switch, means operable upon closing of the main switch for opening the switch in the closing circuit and closing the switch in the holding circuit, a bridge member, the bridge member having an "off position" wherein the terminals are not connected to the current source, an "on position" wherein the terminals are connected to the current source, and a "complete transfer" position, and complete transfer mechanism comprising a master switch having a pair of terminals and a bridge therefor, one of the terminals being connected to a current source and the other terminal being connected to a contact means so positioned as to connect with the closing circuit through the first mentioned member when it is in the complete transfer position, and also connected with the holding circuit through said first mentioned bridge member when it is in the complete transfer position, the first mentioned bridge member being adapted, when in its on position, for contact with a terminal connected to a current source, said terminal being adapted to maintain contact with the first mentioned bridge member until said first mentioned bridge member is in contact with said contact means.

3. An electric circuit controller including a normally open main switch in the circuit to be controlled, a closing coil therefor, a closing circuit for the closing coil comprising a terminal adapted for connection with a current source and a normally closed switch, a holding circuit for the closing coil comprising a terminal adapted for connection with the current source and a normally open switch, means operable upon closing of the main switch for opening the switch in the closing circuit and closing the switch in the holding circuit, a bridge member, the bridge member having an off position, wherein the terminals are not connected to the current source, an on position wherein the terminals are connected to the current source and a "transfer off" position, and transfer off mechanism comprising a master switch having a pair of terminals and a bridge member therefor, one of the terminals being connected to the current source and the other terminal being connected to a terminal so positioned as to connect with the holding circuit, but not with the closing circuit, when the first mentioned bridge member is in transfer off position.

4. An electric circuit controller including

fined in claim 6, characterized by the first mentioned bridge member being movable in either direction and the bridge member for the master switch being movable in one direction only insofar as its movement from on to off position is concerned.

10. An electric switching mechanism as defined in claim 6, characterized by the several positions of the first recited switch mechanism being in the order of off, on, complete transfer, transfer off and transfer on.

11. An electric switching mechanism as defined in claim 6, characterized by the several positions of the first recited switch mechanism being in the order of off, on, complete transfer, transfer off and transfer on, and the bridge member being movable in either direction to such positions.

12. An electric circuit controller, including a normally open main switch in the circuit to be controlled, a closing coil therefor, a closing circuit for the closing coil comprising a terminal adapted for connection with a current source and a normally closing switch, a holding circuit for the closing coil comprising a terminal adapted for connection with the current source and a normally open switch, means operable upon closing of the main switch for opening the switch in the closing circuit and closing the switch in the holding circuit, a bridge member having an off position, an on position and a transfer on position, and a main master switch, the master switch having a complete transfer position with terminals connected to an intermediate contact and said second terminal, the bridge member for the master switch being adapted to connect said terminals at the transfer position to terminals at the main master switch.

13. An electric circuit controlling apparatus comprising a switch having an off position, an on position and a transfer on position, and a master switch adapted to be connected through the first mentioned switch to the circuit to be controlled when said switch is in transfer on position, the master switch having an off position and an on position and also having an intermediate contact adapted to establish a closing circuit when the master switch is moved from off position to on position.

14. An electric circuit controlling apparatus comprising a switch having an off position, an on position and a transfer on position, and a master switch adapted to be connected through the first mentioned switch to the circuit to be controlled when said switch is in transfer on position, the master switch having an off position and an on position and also having an intermediate contact adapted to establish a closing circuit when the master switch is moved from off position to on position, the master switch being adapted for movement from on position to off position

without making electric connection with said intermediate contact.

15. An electric circuit controller including a normally open main switch in the circuit to be controlled, a closing coil therefor, a closing circuit for the closing coil comprising a terminal adapted for connection with a current source and a normally closed switch, a holding circuit for the closing coil comprising a terminal adapted for connection with the current source and a normally open switch, means operable upon closing of the main switch for opening the switch in the closing circuit and closing the switch in the holding circuit, a bank switch having a single handle operable to an off position, an on position, a complete transfer position, a transfer off position and a transfer on position, and a master switch having a pair of terminals and a single handle member adapted to occupy an off position and an on position, one of the terminals of the master switch being connected to a current source and the second terminal thereof being connected to terminal means so positioned as to connect with the closing circuit and also the holding circuit through the bank switch when it is in the complete transfer position, the second terminal being also adapted to connect with the holding circuit, but not with the closing circuit when the handle of the bank switch is in transfer off position, the second terminal of the master switch being also adapted for connection with the holding circuit, but not with the closing circuit when the handle of the bank switch is in transfer on position, the master switch having an intermediate contact adapted for connection with the current source when said handle is moved from off position to on position, said intermediate contact being connected with a terminal for connecting the intermediate contact through the bank switch to the closing circuit when said handle of the bank switch is in the transfer on position.

16. An electric circuit controlling apparatus comprising a single bank switch having relatively movable contact members engaging in different combinations in an off position, an on position, and a complete transfer position, a master switch adapted to be connected to the controlling circuit through said bank switch when it is in complete transfer position, a master switch having different contact members engaging in an off position, an on position and a transfer position, and a main master switch adapted to be connected to the circuit to be controlled through the master switch when it is in the transfer position, said switches each having a single handle for occupying the several positions.

17. In an electrical control system, the combination with an electrical device, of a controlling circuit therefor comprising a plurality of circuit controlling devices each

having a single operating handle and a plurality of relatively movable contact members actuated by their associated handles, and interconnecting conductors, one of the circuit controlling devices being connected to directly control both the energization and de-energization of the electrical device, to transfer through itself the complete control of the electrical device to another of said circuit controlling devices or to transfer through itself the control of the electrical devices to another of said circuit controlling devices for controlling only a predetermined operation.

18. In an electrical control system, the combination with an electrical device, of a controlling circuit therefor comprising a plurality of circuit controlling devices each having a single operating handle and a plurality of relatively movable contact members actuated by their associated handles and interconnecting conductors, one of the circuit controlling devices being connected to directly control the energization and de-energization of the electrical device, to transfer through itself the complete control of the electrical device to another of said circuit controlling devices, or to transfer through itself the control of the electrical device to another of said circuit controlling devices for energizing or de-energizing the electrical device under predetermined operating conditions.

19. In an electrical control system, the combination with an electrical device, of a controlling circuit therefor comprising a plurality of circuit controlling devices each having a single operating handle and a plurality of relatively movable contact members actuated by their associated handles and interconnecting conductors, one of the circuit controlling devices being connected to directly control both the energization and de-energization of the electrical device, to transfer through itself the complete control of the electrical device to another of said circuit controlling devices, or to transfer through itself the control of the electrical device under conditions such that the second circuit controlling device is capable of controlling only a predetermined operation.

20. In an electrical control system, the combination with an electrical device, of a controlling circuit therefor comprising a plurality of circuit controlling devices each having a single operating handle and a plurality of pairs of relatively movable contact members actuated by their associated handles and interconnecting conductors, one of the circuit controlling devices being connected to directly control both the energization and de-energization of the electrical device, to transfer through itself the complete control of the electrical device to another of said circuit controlling devices, or to transfer through itself the control of

the electrical device under conditions such that the second circuit controlling device is capable of energizing or de-energizing the electrical device under predetermined operating conditions.

21. An electric circuit controller, including a normally open main switch in the circuit to be controlled, a closing coil therefor, a closing circuit for the closing coil comprising a terminal adapted for connection with a current source and a normally closing switch, a holding circuit for the closing coil comprising a terminal adapted for connection with the current source and a normally open switch, means operable upon closing of the main switch for opening the switch in the closing circuit and closing the switch in the holding circuit, a bridge member having an off position, an on position, a complete transfer position, a transfer off position and a transfer on position, a master switch and a main master switch, the master switch having a complete transfer position with terminals connected to an intermediate contact and said second terminal, the bridging member for the master switch being adapted to connect said terminals at the transfer position to terminals at the main master switch.

22. In combination, an outside switch and an electric circuit controller comprising bridging means having a group of contact members thereon, a second group of contact members of different effective areas and positions cooperating with and engaging certain of the first named contact members when the bridging means occupies different positions relative to said second group of contact members; a single handle for causing relative movement between the groups of contact members; electrical conductors connected to the contact members in such manner that in one relative position of the groups of contact members a circuit to an electrical device is interrupted; in another relative position of the groups of contact members engagement between co-operating contact members of the group is made for completing a circuit to the electrical device; in another relative position of the groups of contact members engagement between cooperating contact members of the groups is made for completing circuits through the controller through which circuits an electric device may be electrically energized and de-energized by the outside switch; in another relative position of the groups of contact members engagement between cooperating contact members of the groups is made for controlling circuits operable by the outside switch, and effective for maintaining the electrical device electrically energized, if energized when engagement is made, until the device is de-energized by said outside switch, and after the de-energization of the electrical device by said

outside switch it is impossible to re-energize it therefrom; and in another relative position of the groups of contact members engagement between cooperating contact members of the groups is made by which there is established a circuit with a device of such character that the device if de-energized at the time of such relative movement will remain de-energized even though the circuit is closed outside the controller, but will thereafter be energized if the circuit is first opened and then closed.

23. In an electrical system, an electrical device having electrically energized and de-energized positions, a switch, and a circuit controller comprising bridging means having a group of contact members thereon; a second group of contact members of different effective areas and positions cooperating with and engaging certain of the first named contact members when the bridging means occupies different positions relative to said second group of contact members; a single handle for causing relative movement between the groups of contact members; electrical conductors connected to the contact members in such manner that in one relative position of the groups of contact members a circuit to an electrical device is interrupted; in another relative position of the groups of contact members engagement between co-operating contact members of the group is made for completing a circuit to the electrical device; in another relative position of the groups of contact members engagement between cooperating contact members of the groups is made for completing circuits through the controller, through which circuits said electrical device may be electrically energized and de-energized by said switch; in another relative position of the groups of contact members engagement between the contact members of the groups is made for completing circuits controllable by said switch and effective for maintaining the electrical device electrically energized, if energized when engagement is made, until the electrical device is de-energized by said switch, and after the de-energization of the electrical device by said switch it is impossible to re-energize it therefrom; and in another relative position of the groups of contact members engagement between cooperating contact members of the groups is made by which there is established a circuit with the electrical device of such character that the device if de-energized at the time of such relative movement will remain de-energized even though the circuit is closed outside the controller, but will there-

after be energized if the circuit is first opened 60 and then closed.

24. An electric circuit controller as defined in claim 22, characterized by the bridge member being adapted to occupy such positions relative to the second group in the order 65 named and being capable of going from off position to transfer on position.

25. An electric circuit controller as defined in claim 22 characterized by the bridge member being adapted to occupy the various positions relative to the second group outlined 70 in the order named or in a reverse order.

26. An electric circuit controller as defined in claim 22 characterized by the bridge member being adapted to occupy all of said positions relative to the second group, one at a time.

27. An electrical controller system as defined in claim 22, characterized by a master switch adapted to be connected to the electrical device through the first mentioned groups of contact members when it is in a complete transfer position corresponding to the similar positions of the first mentioned groups of contact members, and a main master switch adapted to be connected to the circuit to be controlled through a master switch when it is in the complete transfer position having an off position and an on position for controlling the electrical device through the 90 master switch and the first mentioned groups of contact members when the master switch and the first mentioned groups of contact members are in their complete transfer positions, all of said switches each having a single control handle capable of performing the foregoing operations.

28. An electrical circuit controlling apparatus comprising an electroresponsive switch, a single switch for controlling the electrical 100 energization and de-energization of the electroresponsive switch and having relatively movable groups of contact members for completing an off position, an on position, and a complete transfer position, a master switch 105 adapted to be connected to the circuit to be controlled through said switch when it is in complete transfer position, the master switch having relatively movable groups of contact members for defining an off position, an on position and a transfer position, and a main master switch having relatively movable contact members adapted to be connected to the circuit to be controlled through the master switch when it is in the transfer position.

In testimony whereof I have hereunto set my hand.

JAMES W. STOCKING.
